UNITED STATES PATENT OFFICE

2,160,317

RESPIRATOR

Nathan Schwartz, New York, N. Y.

Application December 18, 1936, Serial No. 116,456

6 Claims. (Cl. 128—146)

This invention relates to filter type respirators adapted to cover the nose and mouth of the wearer for the purpose of protection against dust, fumes and gases and is a modification of my 5 Letters Patent 2,035,097 and my copending applications Serial No. 110,557, filed November 13, 1936, and Serial No. 113,323, filed November 30, 1936.

The invention broadly aims to provide a filter 10 type respirator of minimum size and weight while affording a maximum area of filtration and also to facilitate the replacement of filter material and also minimize the reinhalation of exhaled air and also to provide a neutralizer for acid or 15 similar dangerous fumes and also to provide pressure means at the nose section of the face piece of the respirator to hold said face piece in air tight contact with the face of the wearer. More particularly the invention resides in the 20 emplacement of filter units at the sides of the respirator face piece and there connecting them by means of registering holes and eyelets and placing deformable metal strips into the eyelet lock or other place, which metal strips are directed towards the nose section of the face piece 25 of the respirator, namely to each side of the said nose section for the purpose of supplying needed pressure at the said point in order to obtain an air tight contact between the face piece 30 and the face of the wearer.

Another feature is to raise the filter fabric at the point of marginal attachment by means of an angular deviation at the marginal area of the wall of the filter casing, for the purpose of 35 obtaining immediate filtration at the marginal attachment of the said filter fabric, and also providing supporting strips for the said filter material.

Another feature is the provision of a neutralizing separator unit located in the outlet area of the filter casing.

With the above recited and other objects in view reference is had to the following description and accompanying drawing in which there 45 is exhibited one example or embodiment of the invention, while the claims define the actual scope of the same.

In the drawing:

Figure 1 is perspective view of the improved 50 respirator in applied position.

Figure 2 is a section of line 2—2 of Figure 1.

Figure 3 is a section of line 3—3 of Figure 2.

Figure 4 is a section of line 4—4 of Figure 3, showing supporting strip attached to eyelet connection. 55

Figure 5 is a perspective view of sponge separator pad, prior to emplacement of the sponge into the grit gauze fold. The sponge and its folder is apart.

Figure 6 is a perspective of the sponge and 5 its fold container assembled and forming a separator pad.

Figure 7 is an enlarged section of connecting bolt for separator pad and wall of filter unit.

Figure 8 is a modified form of the supporting 10 strip for the nose section of the body of the respirator. The supporting strip is illustrated here as being attached to the rear side of the casing wall.

Figure 9 shows the filter material supporting 15 strip.

Referring to the drawing by character reference, A designates the face piece of the respirator, B designates the filter unit, C designates the valve, D the head band and E the sponge separator pad. 20

The face piece A of the respirator is preferably constructed of molded rubber or its equivalent and is adapted to engage the face of the wearer and secured thereto by head bands D. 25

The face piece A has a horizontal set back 5 below the nose line which set back 5 has a depending boss 6 which boss is in surrounding relation with a hole 7 in the said set back 5. An exhalation valve C is connected to the body of 30 the respirator at the said horizontal section 5. The said exhalation valve C has a metal tube 8 inserted at its inlet 9, for the purpose of providing a constant potency at such inlet 9. The inlet end 9 of the valve C is inserted into the 35 interior of the boss 6 and by means of cement is attached thereto. The valve C is made of molded elastic rubber and is the army type regulation exhalation valve.

The filter unit B in this respirator has a rear 40 wall 10 and has a marginal rim 11 at the edge of the said rear wall 10 and at the edge of the marginal rim an inturned flange 12 is provided, which flange removably secures a filter fabric 13. It is to be noticed that the rim 11 is outwardly directed and forms an obtuse angle with relation to the wall 10. The said angular arrangement provides an advantageous juncture for correctly securing the said filter fabric. It is required that the said filter fabric 13 be held 45 in spaced relation with its supporting wall 10. This is accomplished by the bolts 14, which bolts extend outwardly from the wall 10 and also by the separator E which separator E is connected to the said wall 10 by the bolts 14. It is also re- 50 55

quired that the said filter fabric obtain immediate filtration at the inner point of its marginal attachment. The reason for this is that a large filter area is needed in order to reduce resistance to breathing. The obtuse angle formation of the rim with relation to its base provides proper and immediate separation of the filter fabric from its attaching wall, which in this instance is the obtuse rim 11. The said filter fabric 13 is impingingly held against said wall by the in-turned flange 12, and due to the outward direction of the rim and also due to the elevations at the inner side of the rear wall 10, the said filter fabric 13 obtains an immediate parting from its attachment.

In this improved respirator there are provided two filter units, one on each side of the face piece A and the connection is made by means of registering holes 15 contained in the rear wall 10 of the filter unit and in the lateral parts of the face piece A. The said holes 15 are joined by eyelets 16.

The rear wall 10 of the casing of the filter unit has a set back 17. The said set back 17 surrounds the outlet hole 15 and is concentric therewith. The said set back 17 is covered by the sponge separator pad E, and the pad E is secured thereto by means of bolts 14. The object of the separator pad E is to purify the exhaled air from its carbon dioxide contents.

It is to be noticed that an air space 18 is formed between the filter fabric 13 and the rear wall 10, and another comparatively small air space 19 is formed behind the sponge pad E. In practise the sponge pad E is moistened with a dilute solution of sodium hydrate and thereby the exhaled air is purified of its carbon dioxide contents. Therefore, the reinhalation of impure exhaled air is minimized and is only equal to the small air space area 19, and thereby continued use of the respirator is made possible without the production of headache and tiredness to the wearer, which headache and tiredness is caused by the carbon dioxide of the reinhaled air. The said alkaline sodium hydrate solution is also useful when the respirator is used for protection against acid fumes, in which instance the acid fume is neutralized by the alkaline solution.

The sponge pad separator E is secured to the wall 10 by means of bolts 14, which bolt is illustrated in Figure 7, the head 20 of the bolt is located at the rear side of the wall 10. The shank 21 is threaded and a nut 22 is secured thereto. A rubber washer 23 is emplaced between the head 20 and the wall 10, for the purpose of making the connection air tight. Also a rubber washer 23a is emplaced between the nut 22 and the grit gauze folder 24 of the sponge pad E. The rubber washer 23a is cut larger than usual and it is thus used for an additional purpose, namely to cover over the nut 22. It is folded and cemented to each other at a point outside of the nut 22. This arrangement is useful because the filter fabric is apt to be damaged by the nut 22 contact. Rubber contact is safer.

The sponge pad E is illustrated in Figures 5 and 6. It has a grit gauze folder 24 wherein is enclosed a sponge separator element 25.

Filter fabrics that are useful for filter type respirators are varied in texture and some are soft and flexible. The soft variety need extra support so that they do not sag and contact the wall 10. If they would contact the wall 10 the filtration area would diminish and thereby the breathing resistance would increase, which must

be avoided. Therefore, additional support for the fabric is required and it is supplied by means of a metal supporting strip 26 which is substantially rigid and is placed behind the filter fabric at the greatest diameter of the marginal rim 11. Usually one metal strip is sufficient, and only one is shown in the drawing, however when required two such metal strips may be inserted and preferably at right angle to one another.

In Figures 3 and 4 are shown metal strips 27. These metal strips are preferably deformable and are locked into the eyelet joint 16. There are two such strips provided, one at each side of the face. These strips are bent to provide rearward pressure at the lateral nasal portion of the face-piece 15 of the respirator, whereby the said face-piece portion is caused to engage the face of the wearer at the said part compressingly and thus a leak proof juncture is assured thereto. That is, the said strips 27 engage the face-piece of the respirator and press upon the said face-piece at the lateral nasal portion thereof, causing thereby a tight leak proof engagement between the face of the wearer and the said face-piece. In Figure 8 there is shown a similar deformable metal supporting strip 27a. This is for the same purpose as the strip 27. But, here the strip is shown to be attached to the rear of the casing wall 10 and attached to the said wall by means of the bolt 14. It engages the face-piece of the respirator at the lateral nasal portion providing rearward pressure thereto to assure a leak proof joint between the said face-piece and the face of the wearer.

Having thus described my invention I claim as new and desire to secure by Letters Patent as follows:

1. A respirator having a hollow mask body of molded elastic material which body is adapted to engage the face of the wearer and the said body has lateral sides and filter units which filter units are connected to the said body at the said lateral sides and the said connections have attachably included deformable supporting elements which elements are directed towards the body of the respirator and pressingly engage the lateral nasal areas of the said body and thereby cause an air tight juncture of the body of the respirator and the face of the wearer at the said nasal areas.

2. A respirator having a hollow mask body of molded elastic material which body is adapted to engage the face of the wearer and the said body has lateral sides and filter units which filter units are connected to the said body at the said lateral sides and the said filter units have substantially rigid inner side walls which walls have attached thereto deformable supporting elements which elements are directed towards the body of the respirator and pressingly engage the lateral nasal areas of the said body and thereby cause an air tight juncture of the body of the respirator and the face of the wearer at the said nasal areas.

3. A respirator having a hollow mask body connected with a filter unit which filter unit has at least one wall and filter material removably secured at the margin of said wall and the said wall has an inwardly directed recess which recess forms an air space having at its inlet and in covering relation therewith a separator and at its outlet an opening connection with the body of the respirator.

4. In a respirator, a hollow mask body having an exhaust valve located at a set back portion below the nose line and an intake port, a filter

unit including a substantially rigid wall with an outlet port and a marginal rim, and supported filter material, and the periphery of said rim has an inturned flange which removably secures the 5 said filter material at the edges thereof and the said filter material confronts the said wall in spaced relation therewith, and the said outlet port connects with the said intake port whereby communication is provided between the said filter 10 unit and the said body, and means provided adjacent the said connection at the outer portion thereof whereby pressure is exerted to the lateral nasal portion of the said body to maintain a leak proof engagement of the said body and 15 the face of the wearer at the said nasal portion. 5. In a respirator a face piece adapted to engage the face of the wearer and made of semi-flexible material having lateral sides, connecting with a filter unit having a substantially stiff wall, 20 and means, the said wall being located in adja-

cent relation with the said face piece at its lateral side and the said means is positioned between the said wall and the said face piece lateral side whereby pressure is brought to bear against the said lateral side and a leak proof engagement 5 is provided between the face of the wearer and the face piece of the respirator.

6. In a respirator, a face piece adapted to engage the face of the wearer and made of semi-flexible material having lateral sides, a filter unit 10 having a stiff wall connected to the said face piece and located adjacent thereto, and means, the said means abutting the said wall and the said lateral sides in a manner whereby pressure is brought to bear against the said lateral sides 15 to provide a leak proof engagement between the face piece of the respirator and the face of the wearer.
